DUAL TOILET TISSUE DISPENSER

Council A. Tucker, Glendale, Calif., assignor to Towel-saver, Inc., Los Angeles, Calif., a corporation of California

Original design application Sept. 28, 1964, Ser. No. 82,142, now Patent No. 203,332, dated Dec. 28, 1965. Divided and this application July 13, 1965, Ser. No. 86,860

Term of patent 14 years

(Cl. D4—3)

FIG. 1.

FIG. 2.

FIG. 3.

FIG. 4.

FIG. 5.

FIG. 1 is an isometric view of the dual toilet tissue dispenser showing my new design;

FIG. 2 is an end elevational view;

FIG. 3 is a top plan view;

FIG. 4 is a bottom plan view; and

FIG. 5 is a front elevational view.

The dominant features of my design reside in the portions shown in full lines and the tissue rolls are included for illustrative purposes only.

This application is a division of co-pending application Serial No. D-82,142 filed September 28, 1964 for "Toilet Tissue Dispenser," now Patent D-203,332.

I claim:

The ornamental design for a dual toilet tissue dispenser, as shown and described.
